UNITED STATES PATENT OFFICE

152,959

DESIGN FOR A BOTTLE

Laurie O. Graf, Wauwatosa, Wis., assignor to John Graf Company, Milwaukee, Wis., a corporation of Wisconsin

Application January 8, 1947, Serial No. 135,998

Term of patent 14 years

(Cl. D58—8)

To all whom it may concern:

Be it known that I, Laurie O. Graf, a citizen of the United States, residing at Wauwatosa, in the county of Milwaukee and State of Wisconsin have invented a new, original, and ornamental Design for a Bottle, of which the following is a specification, reference being had to the accompanying drawing, forming part thereof.

Figure 1 is an elevation of the bottle, and Figure 2 is a top plan view thereof, showing my new design.

The design is characterized by the fact that each corrugation is provided with alternate plain and stippled portions.

I claim:

The ornamental design for a bottle, as shown and described.

LAURIE O. GRAF.
